SHOE SHANK STIFFENER

Reinhard B. Bartels, Marblehead, Mass.

Original application May 8, 1929, Serial No. 361,390. Divided and this application May 23, 1931, Serial No. 539,499

5 Claims. (Cl. 36—76)

Heretofore it has been customary to make metallic shank stiffeners for shoes, when the stiffeners are provided with integral attaching prongs, by cutting them from strip stock of the width of the stiffeners. The attaching prongs, more particularly those of substantial length which must be bent to securely clinch when they are driven into the sole member as at the forward ends of stiffeners for welt or McKay shoes, are cut lengthwise of the strip so that they bend crosswise of the grain of the metal which is produced when it is rolled into sheet form. The narrow width stock is, however, more expensive weight for weight than wider strip stock, since more operations are required to reduce it to a narrow condition. If, however, it be attempted to cut this same form of stiffener widthwise from a relatively wide strip, not only is there considerable waste at the edge or edges where the prongs are formed, but these prongs extend across the grain of the metal and are much less able to withstand bending in the clinching operation without breaking. If, in order to overcome this liability to breakage of the prongs, a relatively soft metal is used, this is considerably more expensive than the harder metal, as it must be subjected to annealing, and further, a greater weight of such softer metal is necessary for the same degree of stiffness of the stiffener. If these relatively long prongs are cut from the body of the stiffener widthwise so that they may be bent across the metal grain, so much of the metal is cut away that the stiffener is liable to break off at the prongs. These drawbacks to the use of wide stock have therefore heretofore prevented its use for the manufacture of integral pronged stiffeners.

This invention has for an object the production of a pronged stiffener which is particularly suitable for cutting widthwise from wide strip stock and wherein the long prongs bend across the grain when being clinched, but which are so constructed that the stiffener is not unduly weakened where the prongs are formed. To this end, each prong is cut from the stock of two adjacent side by side stiffener portions of the strip so that each prong may be of a length equal to one-half the width of the stiffener and yet leave one-half of the width of the stiffener at the prongs uncut. Not only does this construction make possible the cutting of the stiffeners widthwise, but in the case of a stiffener provided with a central longitudinal stiffening rib formed by a lateral bending of the stiffener, it makes possible the successful use of stock harder and less expensive than heretofore required for lengthwise cut stiff-

eners, since in the lengthwise cut stiffeners the rib is formed by bending the metal with the grain, which is likely to cause cracking if the harder stock is used, while in the cross cut stiffeners this rib is formed by bending across the grain. 60

The present application covers the stiffener per se, the method by which it is formed being claimed in my Letters Patent No. 1,829,496 for Method of manufacturing shoe shank stiffeners, issued October 27, 1931, and from which the subject matter of this application has been divided. 65

For a more complete understanding of this invention, reference may be had to the accompanying drawing in which

Figure 1 is a side elevation of a finished stiffener. 70

Figure 2 is a cross section on line 2—2 of Figure 1.

Figure 3 is a perspective of the wide sheet showing successive stages of the cutting and forming of stiffeners therefrom. 75

Figure 4 is a fragmentary plan of one portion of a strip showing one arrangement of the prongs.

Figure 5 is a detail section on line 5—5 of Figure 4. 80

Figure 6 is a fragmentary plan showing a different arrangement of the prongs.

Figures 7 and 8 are detail sections on lines 7—7 and 8—8, respectively, of Figure 5.

Referring to the drawing, at 1 is indicated a strip of sheet metal from which the stiffeners are to be cut. This strip is passed between suitable dies, as shown in my parent application hereinbefore mentioned, by which various cutting and bending operations are successively performed thereon. In the first operation, prongs 11 are struck from one edge portion of the stock of the strip extending lengthwise thereof. At the same time prongs such as 12 may be struck inwardly near the opposite edge of the stock strip opposite to the spaces between the prongs 11. Next prongs 15 from stock lapping the stock cut to form the prongs 11, but extending in the opposite direction, are cut and the stock for the several stiffeners may be partially severed as by the slits 17. The prongs 11 and 15 are thus formed at the extreme end of each completed stiffener. The slits 17 are made opposite to the central portions of the side lapping lengths of material from which the prongs 11 and 15 are formed. The partly severed stiffeners may then have stiffening ribs 18 molded therein and thereafter they may be molded to lateral curvature and then individually completely severed from the strip in completed condition. 110

The prongs 11 and 15 can be cut as shown in Figures 4 or 5, all the diagonal lines of severance 30 between the portions struck out extending in parallel relation. When the stiffeners are so cut 5 the points of the prongs are offset from each other lengthwise of the stiffener, as shown in Figure 5, each stiffener having its prongs 11 and 15 arranged in the same relation thereto as all the others. Instead of so cutting the prongs, the diagonal 10 cuts may be alternately reversely positioned as shown at 30 and 31 in Figure 6. In this case both prongs of each stiffener come opposite to each other lengthwise of the stiffener, but those of one stiffener have their diagonal edges facing 15 outward toward the adjacent end of the stiffeners as shown at 32 in Figure 7 and the stiffeners cut from the strip portions next adjacent thereto have the diagonal sides of the prongs inwardly facing as at 33 in Figure 8. In both cases, however, 20 it will be noted that one-half the length of each prong is cut from the stock of the next adjacent strip portion thereto, so that these prongs may be made each of a length of one-half the width of the strip portion and yet between the 25 opposed prongs of each strip portion there is left an uncut space equal in width to the length of each of the long prongs and so equal in length to one-half the width of the completed stiffener. The combined lengths of the prongs and the body 30 portion therebetween is thus substantially one and one-half times the maximum width of the body portion of the stiffener, the length of each prong being substantially one-half of this maximum width and the prongs being spaced apart 35 one-half of this width. Moreover, as the grain of the metal runs lengthwise of the strip 1, the line of bending of each of these prongs is transverse to the line of this grain so that the prongs can be bent, when the stiffener is fixed to the sole 40 member by clinching the prongs over, without danger of breakage. These relatively long prongs should be placed at the forward ends of the stiffeners which are to be used for welt or McKay shoes. The rear end fastening means for 45 the stiffeners is not required to be so secure, since this portion comes over the heel and is securely fixed by the neighboring portions of the shoe. A relatively short prong which it is not necessary to clinch in the material is therefore all that is necessary. 50 These short prongs may be formed in various ways, therefore, Figures 6 and 7 showing a different form from that illustrated in Figure 1. Referring to these Figures, it will be seen that the material of the stiffener is struck out at 35 in 55 opposite directions to form pairs of short prongs 36.

Each of the completed stiffener members, it will be seen, comprises a laterally extending strip 1, section 51 cut from the relatively wide strip 1, 60 and has a centrally depressed reinforcing rib 18, a pair of spaced relatively long integral attaching prongs 11 and 15 at one end bent from portions of

greater width than the body portion of the stiffener and relatively short integral attaching prongs as 12 adjacent to its opposite end. If it were attempted to strike the long prongs from the material of the width of one individual strip portion there would be insufficient material to make these prongs of the necessary length. As the strip material 1 as commercially made varies slightly in width, it should be fed into the die pressed against the left hand edge as viewed in Figure 3, so that the prongs 11 and 15 may all be of full size. The prongs at the opposite end of the stiffener being formed slightly inward from the end of the stiffener and inwardly from the edge of the strip 1 are therefore not affected by the slight commercial variations in width of the strip 1. 80 90

From the foregoing description of certain embodiments of the stiffener together with a method and means by which such stiffeners may be formed, it should be evident to those skilled in the art that various changes and modifications might be made therein without departing from the spirit or scope of this invention as defined by the appended claims. 95

I claim:

1. A shank stiffener having a body portion, and opposed pairs of attaching prongs integral with said body portion and spaced apart substantially one-half the width of said body portion, each of said prongs being of a length substantially one-half the width of said body portion and at the extreme end of said stiffener. 100
2. A sheet metal shank stiffener having the grain of the metal extending laterally thereof, and provided with integral attaching prongs extending lengthwise of said grain at one extreme end. 110
3. A shank stiffener having a body portion arranged with the grain of the metal extending laterally thereof, and having attaching prongs 115 extending from the sides of said body portion at one end, the combined lengths of said prongs and the body portion therebetween being greater than the width of said body portion.
4. A shank stiffener having a body portion arranged with the grain of the metal extending laterally thereof, and having attaching prongs extending from the sides of said body portion at one end, the combined lengths of said prongs and the body portion therebetween being greater than the width of said body portion, said stiffener also having attaching prongs inwardly of its opposite end. 120
5. A shank stiffener having a body portion arranged with the grain of the metal extending laterally thereof, and having attaching prongs 130 extending from the sides of said body portion at one end, the combined lengths of said prongs and the body portion therebetween being substantially one and one-half times the maximum width of said body portion. 135
